UNITED STATES PATENT OFFICE.

LEWIS W. THOMAS, OF WASHINGTON, DISTRICT OF COLUMBIA, ASSIGNOR OF ONE-HALF
TO OSCAR T. WRIGHT, OF WASHINGTON, DISTRICT OF COLUMBIA.

BUCKLE.

1,209,075.

Specification of Letters Patent. Patented Dec. 19, 1916.

Application filed January 28, 1916. Serial No. 74,837.

To all whom it may concern:

Be it known that I, LEWIS W. THOMAS, a citizen of the United States, residing at Washington, in the District of Columbia, 5 have invented new and useful Improvements in Buckles, of which the following is a specification.

This invention relates to improvements in buckles and has particular application to a 10 buckle stamped from a single piece of metal.

In carrying out the present invention, it is my purpose to provide a buckle which may be stamped from a single sheet of metal, which will be found especially useful in connection with the belts used on printing 15 presses for feeding the paper to the press and taking the paper from the press, which may be secured to the ends of the belt without the necessity of sewing or stitching, 20 which will lie flat so as to present no irregular surfaces, and which may be adjusted upon the belt quickly and conveniently when it is desired to take up any slack in the belt.

With the above and other objects in view, 25 the invention consists in the construction, combination and arrangement of parts hereinafter set forth in and falling within the scope of the claims.

In the accompanying drawing: Figure 1 30 is a fragmentary plan view showing two ends of the belt connected together by means of a buckle constructed in accordance with the present invention. Fig. 2 is a longitudinal sectional view through the same. Fig. 35 3 is a cross sectional view therethrough. Fig. 4 is an enlarged perspective view of the buckle removed from the belt.

My improved buckle is formed from a single piece of metal or plate 1 stamped to 40 form transverse slots 2 adjacent to the respective ends of the plate and transverse slots 3 arranged adjacent to the respective slots 2 and inwardly thereof. These slots 3 are preferably of less width than the slots 45 2. The center portion of the plate 1, that is, the portion between the slots 2 is in the form of a web 4 and stamped outwardly from the

web 4 in relatively opposite directions adjacent to the respective slots 3 are teeth 5.

In the use of the buckle, one end of the 50 belt is drawn through one of the slots 2 and then carried through the adjacent slot 3, across the web 4, through the other slot 3 and then through the remaining slot 2. The belt is now drawn taut through the buckle 55 and the teeth 5 on the side of the web bite into the material of the belt to prevent accidental removal of the buckle from the belt. The other end of the belt is trained through the last-mentioned outer slot 2, across the 60 web and then through the other slot 2 and the corresponding set of teeth 5 bite into the material of the belt between the slots 2 so as to hold this end of the belt connected to the buckle. When it is desired to take up 65 any slack in the belt, the last-mentioned end thereof may be loosened between the slots 2 and then drawn through the slots until the belt has been placed under the desired tension.

It will be noted that this buckle is flat so that no uneven or irregular surfaces are presented to the wheels over which the belt travels, or to the paper, while the buckle is so constructed as to hold the ends of the belt 75 securely connected to each other. The extremities of the belt projecting beyond the buckle may be clipped off adjacent to the respective end of the buckle so that there will be no loose ends.

While I have herein shown and described one preferred form of my invention by way of illustration, I wish it to be understood that I do not limit or confine myself to the precise details of construction herein described and delineated, as modification and variation may be made within the scope of the claims and without departing from the spirit of the invention.

I claim:

1. A belt buckle formed of sheet metal stamped to provide transverse slots adjacent to the respective ends thereof and similar slots adjacent to the first-mentioned slots re-

spectively and inwardly thereof and spaced apart from each other, and sets of teeth stamped from the metal between said inner slots and projecting outwardly from opposite sides of the metal.

2. A belt buckle formed of sheet metal stamped to provide transverse slots adjacent to the respective ends thereof and similar slots adjacent to the first-mentioned slots respectively and inwardly thereof and spaced

apart from each other, and sets of teeth stamped from the metal between said slots and projecting outwardly from opposite sides of the metal.

In testimony whereof I affix my signature in presence of two witnesses.

LEWIS W. THOMAS.

Witnesses:

M. P. WARD,
O. T. WRIGHT.
